UNITED STATES PATENT OFFICE.

JOHN FRANCIS GREATHEAD, OF ROME, NEW YORK.

DAM.

1,010,254.

Specification of Letters Patent. Patented Nov. 28, 1911.

Application filed May 2, 1911. Serial No. 624,538.

To all whom it may concern:

Be it known that I, JOHN F. GREATHEAD, a citizen of the United States, and a resident of Rome, in the county of Oneida and 5 State of New York, have invented a new and Improved Dam, of which the following is a full, clear, and exact description.

The invention relates to concrete structures and its object is to provide a new and 10 improved dam arranged to utilize the passive pressure of the ground to hold the dam in position against the water pressure and to prevent seepage of the water underneath the bottom of the dam.

15 In order to accomplish the desired result the dam is formed of a monolithic cantilever structure having an upper portion for the water pressure, and a lower portion built in the ground a distance sufficient for 20 the passive pressure of the ground on both faces of the lower portion to overcome the overturning tendency of the water pressure on the upper portion.

25 A practical embodiment of the invention is represented in the accompanying drawings forming a part of this specification, in which similar characters of reference indicate corresponding parts in all the views.

Figure 1 is a vertical section of the dam; 30 Fig. 2 is a like view of a modified form of the dam provided with a non-monolithic apron; Fig. 3 is a similar view of a modified form of the dam provided with a monolithic apron; and Fig. 4 is a similar view of 35 a modified form of the dam provided with a monolithic apron, and an upper portion inclined in an upstream direction for a high velocity of approach.

The dam A, illustrated in Fig. 1, is in 40 the form of a monolithic cantilever structure or slab, preferably of reinforced concrete, and consisting of an upper lever portion B extending across the waterway C, and a lower lever portion D embedded in 45 the ground or embedment E a distance sufficient for the passive pressure of the ground on both faces of the lower portion D to overcome the overturning tendency of the water pressure against the up-stream face of 50 the upper portion B.

In case the embedment of the lower portion D of the lever A is sand or earth then the portion extends downward a distance in proportion to the upper portion B, as indicated in Fig. 1, but when the embedment 55 is rock a channel is formed in the rock, say

to a depth indicated by the line a—a, and in this channel extends the lower portion D of the dam. It is understood that the passive pressure of the rock is considerably 60 greater than the passive pressure of sand or earth, and hence the lower portion D must necessarily extend farther down in the ground, if the latter is of sand or earth, than when the embedment is of rock. 65

In the modified form shown in Fig. 2, the dam A' is similar to the one shown in Fig. 1, that is, it consists of an upper portion B' and a lower portion D', of which the upper portion B' extends across the waterway C' 70 and the lower portion D' is embedded in the ground or bed E'. On the down stream side of the dam A' is arranged a water apron F, preferably made separate from the dam and not necessarily reinforced. The 75 down stream lower end may be provided with a water cut-off F' to prevent water from passing under the apron F, and the lower end may also be provided with drain openings F² for draining the apron F. 80

In the modified form shown in Fig. 3, the dam A², having the portion B² and D², is provided with a water apron G made integral with the dam A² and having its bottom inclined in an upward and down-stream 85 direction, the end G' of the apron, extending as a water cut-off into the ground E², and having drain openings G². It is understood that in this case the pressure of the water in the waterway C² against the upper 90 portion B² of the dam is resisted by both the lower portion D² and the apron G.

In the modified form shown in Fig. 4, the upper portion B³ of the dam A³ is inclined upwardly and in an upstream direction 95 across the waterway C³, while the lower portion D³ of the apron H with its water cut-off H' is similar to the corresponding parts shown in Fig. 3, and is provided with drain openings H². 100

It is understood that the dams illustrated in Figs. 2 and 3 are more especially designed for a low velocity of approach, while the dam illustrated in Fig. 4 is more especially designed for a high velocity of approach. 105

It is understood that the upper portion B, B', B² or B³ of the dam varies in shape and inclination according to the use of the dam as a mere reservoir dam or as a spillway, and in the latter case according to the 110 velocity of the approaching water. It is further understood that when the ground

or bed is sand or soft earth and the water apron is quite a distance below the surface, the passive pressure on the downstream face of the portion from b to b (see Figs. 3 and 5 4) is replaced by pressure on the water apron G or G' , which transmits the ground's passive pressure to the portions B^2, D^2 and B^3, D^3 . When the velocity of the approaching water is high the angle of inclination to the horizontal of the upstream face of the upper portion of the dam is less than 90° to keep the water-sheet against the downstream face of the spillway.

It will be noticed that by extending the 10 lower portions D, D', D^2 or D^3 down into the ground as described a very effective seepage cut-off is produced and hence loss of water and undermining is reduced to a minimum, and it will further be noticed that 15 the said lower portions are built in the ground to a depth sufficient, that the pressure of the ground acting normally on both faces of the lower portions overcomes the overturning tendency of the water pressure 20 on the upper portions B, B', B^2 and B^3 , solely by resistance to bending strains in the body of the structure. The lower ends or crests of the aprons F, G and H are raised 25 above the elevation of the ground E', E^2 and E^3 , whereby the surface of the water in the 30 apron is above the elevation of the ground. By the arrangement described the fall of the water is reduced and less excavation is required.

35 Having thus described my invention, I claim as new and desire to secure by Letters Patent:—

1. A dam, comprising a monolithic cantaliver structure having an upper and a lower 40 portion, the upper portion being exposed to the water pressure and the lower portion being built in the ground to a depth sufficient that the pressure of the ground acting normally on both faces of the lower portion 45 overcomes the overturning tendency of the water pressure on the said upper portion solely by resistance to bending strains in the body of the said structure.

2. A dam, comprising a monolithic cantaliver structure having an upper and a lower portion, the upper portion being exposed to the water pressure and the lower

portion being built in the ground to a depth sufficient that the pressure of the ground on both faces of the lower portion overcomes 55 the overturning tendency of the water pressure on the said upper portion, and a water apron on the down stream side of the said structure.

3. A dam, comprising a monolithic cantaliver structure having an upper and a lower portion, the upper portion being exposed to the water pressure and the lower portion being built in the ground to a depth sufficient that the pressure of the ground on both faces of the lower portion overcomes 60 the overturning tendency of the water pressure on the said upper portion, and a water apron integral with the said structure on the down stream side thereof.

4. A dam, comprising a monolithic cantaliver structure having an upper and a lower portion, the upper portion being exposed to the water pressure and the lower portion being built in the ground to a depth sufficient 70

that the pressure of the ground on both faces of the lower portion overcomes the overturning tendency of the water pressure on the said upper portion, and a water apron integral with the said structure on the down stream side thereof, the elevation 75 of the water surface over the apron being higher than the elevation of the ground.

5. A dam, comprising a monolithic cantaliver structure, having an upper and a lower portion, the upper portion being exposed to the water pressure and the lower portion being built in the ground to a depth sufficient that the pressure of the ground on both faces of the lower portion overcomes 80 the overturning tendency of the water pressure on the said upper portion, and a water apron extending integrally upwardly and in a down-stream direction from the said lower portion of the dam and in contact with the 85 ground.

In testimony whereof I have signed my name to this specification in the presence of two subscribing witnesses.

JOHN FRANCIS GREATHEAD.
